BODY BOLSTER

John A. Lamont, Chicago, Ill., assignor to American Steel Foundries, Chicago, Ill., a corporation of New Jersey

Application August 7, 1931, Serial No. 555,661

12 Claims. (Cl. 105—406)

The present invention relates to railway cars, and more in particular to the construction of heavy capacity cars of the type in which the bolster is entirely within the car body.

5 Among the objects of the present invention is to provide a bolster of novel construction for a car body, adapted to withstand and resist unsymmetrical loading, local bending and crushing or other stresses and strains to which the same

10 may be subjected.

Heretofore, it has been the practice to provide a heavy capacity railway car with an inside bolster consisting of two trusses integrally united at the center by a portion of rectangular shape

15 resting over the center sill of car. This type of bolster has not proven successful in resisting unsymmetrical loading, such as occurs when the car body is subjected to a rocking action, during

20 which movement the load is taken alternately on one or the other of the side bearings. The concentration of load over the relatively narrow center sill also makes it necessary to introduce a new and different structure at the central portion of the bolster better to withstand or resist

25 local bending and crushing.

It is therefore an object of the present invention to eliminate the objectionable features of the old type bolster construction and to provide a novel bolster structure adapted to meet all the

30 requirements of service, yet of simple design and adapted to usual foundry methods of molding.

In the embodiments selected to illustrate the invention, the bolster is shown as comprising a member of truss formation having a central box-

35 like or double web section including certain of the struts of the structure as elements thereof. A box-like section at the central portion of the bolster and over the center sill, whether or not the section be rectangular or triangular in form,

40 has been found to provide a construction very well adapted to withstand those loadings to which the same may be subjected.

The invention contemplates the idea of providing a one-piece inside bolster construction including a central box-like or double web section and integral wing plates extending therefrom.

Another object of the invention is to provide an inside bolster for car bodies comprising a member of truss formation with a central box-like or double web section and having wing members extending therefrom whose inner marginal portions are in alignment with struts of the member.

45 A still further object of the invention is to provide an inside bolster including a central box-

like or double web section extending between and having portions terminating adjacent side bearings provided on the bolster.

The invention still further comprehends the idea of providing an inside bolster of truss formation having struts terminating and merging at a common point adjacent the side bearings provided on the bolster, and irrespective of whether or not certain of these struts are in alignment with the inner marginal portions of wing members extending from the bolster.

5 With these and various other objects in view, the invention may consist of certain novel features of construction and operation as will be more fully described and particularly pointed out in the specification, drawings and claims appended hereto.

10 In the drawings, which illustrate an embodiment of the device and wherein like reference characters are used to designate like parts—

20 Figure 1 is a view in vertical cross-section taken through a car body disclosing in side elevation an embodiment of the present novel bolster;

25 Figure 2 is a fragmentary view in side elevation of the car body of Figure 1 and adjacent the inside bolster thereof;

Figure 3 is a view in cross-section taken in the plane represented by line 3—3 of Figure 1 of the drawings;

30 Figure 4 is a view partly in cross-section and partly in elevation and taken in a plane represented by line 4—4 of Figure 1 of the drawings;

Figure 5 is a view in cross-section taken in the plane represented by line 5—5 of Figure 1 of the drawings;

35 Figure 6 is a view in cross-section taken in a plane represented by line 6—6 of Figure 1 of the drawings;

Figure 7 is a fragmentary bottom plan view of the inside bolster disclosed in Figure 1 of the drawings;

40 Figure 8 is a view in cross-section taken through a car body and disclosing in side elevation a modification of the inside bolster disclosed in Figure 1 of the drawings;

45 Figure 9 is a view in cross-section taken in a plane represented by line 9—9 of Figure 8 of the drawings;

50 Figure 10 is a fragmentary view in cross-section taken through a car body and disclosing in side elevation another modification of the bolster of the present invention;

55 Figure 11 is a view in cross section taken in the planes represented by lines 11—11 of Figure 10 of the drawings;

Figure 12 is a fragmentary view in cross-section taken through a car body and disclosing in side elevation a still further modification of the bolster of the present invention;

5. Figure 13 is a fragmentary view partly in cross-section and partly in side elevation and taken in a plane represented by line 13—13 of Figure 12 of the drawings;

Figure 14 is a view in vertical cross-section taken through a car body and disclosing in side elevation still another embodiment of the bolster of the present invention;

Figure 15 is a view in cross-section taken in a plane represented by line 15—15 of Figure 14 of the drawings; and

Figure 16 is a view in cross-section similar to Figure 15 of the drawings and disclosing an alternative construction of the box-like structure of the central portion of the bolster shown in Figure 15 of the drawings.

15 or the drawings.
Referring now more in detail to the drawings, an embodiment of the present novel bolster construction is disclosed in a car body having side plates 2 connected in any suitable manner along their upper edges to top flange angles 4 and reinforcing gusset plates 6, the lower edge of the sides 2 being connected to bottom flange angles 1 which angles in combination with plates 2 and top angles 4 form the load carrying members of the car. Each of the bottom plates 8 of the car body extend inwardly from the flange angle 1 and terminates in overlapped relation with a center sill cover plate 10 mounted or supported upon a center sill generally designated as 12 and comprising channel members 14 within which is a center filler casting 16. The center sill channels 14 are provided with a lower cover plate 18. The usual center plate 20 rests on the cover plate and is secured to center sill by rivets or bolts.

40. The inside bolster of the present invention comprises a member 22 of truss formation having a top chord 24 and a lower chord 26 integrally connected by the diagonal struts 28, 30, 32 and 34. The ends of the members 24 and 26 are connected 45 by the vertical struts 36 and 38. At the ends of the truss member and integral therewith are provided wing plates or inner side stakes 40 and 42 extending upwardly therefrom to terminate at their upper ends adjacent the top flange angles 50. 4. The outside members of the bolster structure are of flange formation and are connected, as by means of rivets, or the like, to the side and bottom plates of the car body.

55 The central portion of the member 22 is provided with a box-like or double web section 44, this section comprising the spaced webs 46 and 48 terminating at their upper and lower edges in the top and bottom chords 24 and 26, respectively, of the truss member. This box-like or 60 double web section further includes the diagonal plate portions 50 and 52 adapted to act as diagonal struts for the truss member and terminating in the upper and lower chords thereof. Each of the webs 46 and 48 is provided with an opening 54, 65 between which extends a transverse wall 56 defining these openings and reinforcing, together with the corner brackets 58, the oppositely spaced webs 46 and 48.

70 In the present embodiment, the central portion
44, which is box-like in construction, is formed
integral with the remaining portions of the bol-
ster, and openings 57 are provided in the lower
chord member 26 for removal of the core used in
75 the formation of this box-like central portion.

In the present embodiment, diagonal struts 30 and 32 are shown as being in alignment with the inner flanged portions 59 of the substantially triangular shaped wing plates 40 and 42 and the same terminate at their lower end at a common point with the struts 58 and 52 of the box-like section 44 and immediately adjacent side bearings 60 and 62 provided on either side of the center sill 12. Further, the diagonal struts 28 and 34 terminate at a common point in the upper chord 10 24 with the diagonal struts 30 and 32 and with the inner flanges of the wing plates 40 and 42, respectively, while the lower ends of these struts are cored, as shown at 64, to remove the bulk of the metal at these points and to avoid shrinkage difficulties which otherwise would result from the uniting of a plurality of members as exists at this point. 15

In the embodiment disclosed in Figures 8 and 9, the bolster of the present invention is of a construction similar to the construction shown in Figure 1 of the drawings and varies therefrom in that the diagonal struts 65 and 66, instead of terminating at their upper ends at a common point with the diagonal struts 68 and 70 as shown in the previously described embodiment, extend downwardly and inwardly from the outer corner of the truss member 72 to terminate at a point in the lower chord of the truss member 72 removed a short distance from the lower ends of the struts 68 and 70. As in the previously disclosed embodiment, the bolster is provided with a central box-like section or structure 44 immediately above the center sill 12 and for withstanding and resisting unsymmetrical loadings at this point, as likewise local bending and crushing.

In the embodiment disclosed in Figures 10 and 11, the truss member 74 is of a similar construction as the truss member 72 of Figure 8 of the drawings, and the bolster of this embodiment varies from that shown in Figure 8 merely in providing separate wing plates 76 adapted to be secured to the top chord of the truss member 74, as by means of rivets 78, or the like.

In Figures 12 and 13 of the drawings is disclosed a still further embodiment of the present invention, the same varying from the embodiment disclosed in Figures 8 and 10 in that vertical struts 80 are provided in place of the diagonal struts, such as 68 and 70, as shown in Figure 8 of the drawings. The vertical struts 80 terminate at their lower ends in a similar manner as the diagonal struts, such as 68 and 70 of Figure 8 of the drawings, and immediately adjacent the central box-like section or double web structure 44 and immediately above the side bearings 82, these vertical struts, however, not being in alignment with the inner marginal flange portion 84 of the integral wing plates 86. As in the previous embodiments, however, this arrangement provides a very suitable construction for effectively withstanding the loadings to which the holster is subjected.

The embodiment of the present invention disclosed in Figures 14 and 15 is similar to the embodiment disclosed in Figure 1 of the drawings, with the exception that in this embodiment of the bolster, the core for the central box-like section or structure 88 is removed through the openings 90 provided in the webs 92 and 94 thereof. In order to reinforce the webs 92 and 94 and provide a rigid structure, these webs are connected by means of the connecting pieces 96 formed integral therewith. After the core has been removed from within the space between the 75

webs 92 and 94, the openings 90 thereof are closed as by means of plates 98 placed thereover and welded thereto for preventing accumulation of dirt or other material within this box-like structure 88.

As shown in Figure 16 of the drawings, the webs 92 and 94 may be provided with annular beads 100 cast or formed integral therewith and adapted to receive the plates 102 therebetween, these plates 102 being suitably welded to the annular projecting beads 100.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

20 I claim:

1. In a car body construction, the combination of a bolster of truss construction, side bearings for said bolster, said bolster having diagonally disposed struts terminating adjacent said side bearings, a central box-like section including certain of said struts, wing members extending from said bolster, and a center sill for support of said car body.

2. In a car body construction, the combination of a bolster of truss construction, side bearings for said bolster, said bolster having struts terminating adjacent said side bearings, a central box-like section varying in width including certain of said struts, wing members extending from said bolster and having their inner marginal portions in alignment with certain other of said struts, and a center sill for support of said car body.

3. In a car body construction, the combination of a bolster of truss construction, side bearings for said bolster, said bolster having diagonal struts terminating at a common point adjacent said side bearings, a central box-like section including certain of said diagonal struts, wing members extending from said bolster, and a center sill for support of said car body.

4. In a car body construction, the combination of a bolster of truss construction, side bearings for said bolster, said bolster having diagonal struts terminating at a common point adjacent said side bearings, a central box-like section including certain of said diagonal struts, wing members extending from said bolster and having their inner marginal portions in alignment with certain other of said struts, and a center sill for support of said car body.

5. A bolster for a car body, comprising a member having end portions, side bearings therefor,

and a box-like central portion between said end portions and having diagonally disposed strut portions terminating adjacent said side bearings.

6. A bolster for car body, comprising a member having end portions, wing portions extending upwardly therefrom, side bearings for said member, and a box-like central portion between said end portions having diagonally disposed strut portions terminating adjacent said side bearings. 10

7. A bolster for a car body, comprising a member of truss formation having diagonally disposed struts, a box-like central portion, wing portions having parts thereof in alignment with certain of said struts and side bearings. 15

8. A bolster for a car body, comprising a member of truss formation having diagonally disposed struts, a box-like central portion, wing portions having parts thereof in alignment with certain of said struts, and side bearings in alignment 20 with said last-named struts.

9. A bolster for a car body, comprising a member of truss formation having a top and bottom chord, diagonally disposed struts extending between said chords, side bearings associated with 25 said bottom chord, a box-like central portion between said chords and having diagonally disposed strut portions terminating adjacent said side bearings, and wing portions having parts thereof in alignment with certain of said struts. 30

10. A bolster for a car body, comprising a member of truss formation having a top and bottom chord, diagonally disposed struts extending between said chords, side bearings associated with said bottom chord, a box-like central portion between said chords, said central portion having diagonally disposed strut portions, said strut portions and certain of said struts terminating adjacent said side bearings, and wing portions having parts thereof in alignment with 40 said last-named struts. 35

11. A bolster for a car body, comprising a member having an upper and lower chord, diagonally disposed struts between said chords, spaced webs extending between certain of said struts, 45 said webs varying in width from said top to said bottom chord, and side bearings adjacent the lower corners of said webs.

12. In a car body construction, the combination of a bolster of truss construction, side bearings for said bolster, said bolster having diagonal struts terminating adjacent said side bearings, substantially vertical struts between said diagonal struts, a central box-like section including certain of said diagonal struts, wing 55 members extending from said bolster, and a center sill for support of said car body. 50

JOHN A. LAMONT.
